(57) CLAIM

The ornamental design for a toilet, as shown and described.

DESCRIPTION

FIG. 1 is a front perspective view of a toilet showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 shown in FIG. 8. The dot-dash broken line encircling the enlargement forms no part of the claimed design.
